UNITED STATES PATENT OFFICE

171,900

ARMCHAIR

William James Leather, Stanmore, England

Application July 17, 1952, Serial No. 20,653

Term of patent 14 years

(Cl. D15—8)

To all whom it may concern:

Be it known that I, William James Leather, a British subject, residing at Stanmore, Middlesex, England, have invented a new, original, and ornamental Design for an Armchair, of which the following is a specification, reference being had to the accompanying drawing, forming part thereof.

Fig. 1 is a front perspective view of an armchair, showing my new design; and

Fig. 2 is another perspective view thereof taken opposite to Fig. 1.

I claim:

The ornamental design for an armchair, substantially as shown.
